UNITED STATES PATENT OFFICE.

ARNOLD J. FRITH, OF SELMA, ALABAMA.

LOCK.

Application filed September 22, 1926. Serial No. 137,097.

The object of this invention is to provide a device including a casing, carrying a spring mounted yoke member and a plurality of barrels having their axes in alinement, one of the barrels being retained by spring-held pins to be controlled by a key, this barrel controlling the other barrels thru which locking engagement with the yoke is effected.

With the foregoing and other objects in view, the invention consists in the novel construction and arrangement of elements described, illustrated and claimed, it being understood that modifications may be made within the scope of the claims without departing from the spirit of the invention.

In the drawings forming part of this application;

Figure 1 is a view showing the casing of the lock in vertical or longitudinal section, with the yoke in elevation.

Figure 2 is an edge elevation of the structure of Figure 1.

Figure 3 is a section on line 3—3 of Figure 1.

Figure 4 is a section on line 4—4 of Figure 1.

Figure 5 is a section thru the casing, with the yoke in release position, and the barrels in elevation.

Figure 6 is a bottom plan view of the structure of Figure 5.

Figure 7 is a section on line 7—7 of Figure 6.

Figure 8 is a section on line 8—8 of Figure 1.

Figure 9 is a section on line 9—9 of Figure 1.

Figure 10 is a fragmentary view showing a slotted portion of the casing, and a lug for engagement by the pivoted element of Figure 9.

The housing or casing is designated 10, and is provided with a bore 11, in which the longer end portion or shank 12 of the yoke 13 is mounted. A coil spring 14 within bore 11 bears on the lower end of yoke 13 and especially on the lower end of the shank 12 thereof, and tends to force the yoke into an upper and release position, when the device is unlocked. The shank 12 carries a pin or lug 12', and the latter projects thru the curved or cam slot 15 in the casing, this slot being illustrated in Figure 2, and elsewhere. The yoke 13 carries a collar 13' adapted to fit over the upper end of casing 10, and close any space otherwise existing around the

shank 12, so that the insertion of a tool or other element, is prevented.

The opposite end portion of the yoke 13 is cut away, as shown in Figures 1, 3 and 5, to form bayonet slots designated 17, and adapted for cooperation with the engaging devices referred to below.

A lower barrel 20 is rotatable in a vertical bore in the casing 10, and is key controlled, and an upper barrel 21 is controlled by the lower barrel, so that upon the insertion of a key 22 which properly controls the pin tumblers or spring pins, the lower barrel 20 is released and is permitted to rotate, at which time the lug 24 depending from the upper barrel 21 is engaged by spring 25 on the lower barrel 20, and said barrel 21 is operated or caused to move angularly until pin 21' is released from the adjacent bayonet slot 17 on the end of the yoke. The rotation of upper barrel 21 also results in the release of bolt 27 from the engaging position of Figure 1, so that the shank 12 of the yoke 13 is lifted by spring 14, and is swung to the position of Figure 5, in view of the cooperation between pin 12' on the shank 12, and the cam slot 15.

Barrel 20 is provided with longitudinal bores or channels receiving pins 30 with which springs 31 cooperate, the springs controlling the pins, when not controlled by the key 22. The pins 30 are slotted transversely at 32, and the bolt, bar, or dog 33 cooperates with the slots when the latter register, the release position of bolt 33 being shown in Figure 8, said element 33 passing into the recess 34 and engaging shoulder 35 when free to act under the influence of spring 36. The bolt 33 recedes when the key causes the slots of the pins to register and when the barrel 20 is rotated by the key. In this connection it will be noted that slot or recess 34, is provided with a cam wall.

Upon rotating barrel 20, engagement between elements 24 and 25 of Figure 4 is affected, and the upper barrel 21 is rotated until it comes to position permitting release of pin 21' from the adjacent bayonet slot 17, and the release of pin 21'', in a similar manner.

The rotation of the upper barrel 21 also moves the recessed portion 38 into position opposite the left end of bolt 27, so that the latter moves to the left in Figures 1 and 3, and is released from the recess 27' in the shank 12, the release position being shown

in Figure 5. Spring 39 permits of this movement of element 27 to the left.

A pivoted arm or dog 40, shown especially in Figures 1 and 9, project thru an opening in the side of upper barrel 21, and is adapted to project into the slot 41 in the wall of casing 10, and to cooperate with and engage shoulder 42, the inner end of element 40 acting under the influence of the spring 43. This spring, as well as the pivoted element 40, is mounted in a recess in barrel 21 which receives the end or short end of the yoke 13. In order to protect the upper barrel 21, plate 45 is secured to the upper end of the casing 10, and is provided with apertures for opposite portions of the yoke, as will be apparent from the drawings.

The end of the yoke 13, when the latter is being moved to locking position, releases dog 40 from shoulder 42, and permits movement of the barrel to locking position, under the action of spring 47. The release of the lock by means of key 22, to be inserted thru slotted key plate 22', has been described.

Having described the invention what is claimed is:—

1. In a lock, a casing, a spring operated yoke mounted in the casing and including a shank, an upper barrel and a lower barrel in alinement therewith, means for moving the upper barrel by the rotation of the lower barrel, spring controlled and key controlled pins mounted in the lower barrel, a bolt for engaging the shank, retaining the yoke in locked position, the upper barrel having a recess into which the bolt is movable for releasing the shank of the yoke.

2. In a lock, a casing, a spring operated yoke mounted in the casing and including a shank, an upper barrel and a lower barrel in alinement therewith, means for moving the upper barrel by the rotation of the lower

barrel, spring controlled and key controlled pins mounted in the lower barrel, the upper barrel being recessed for receiving one end of the yoke, devices formed on the inner wall of the recess and on the adjacent end of the yoke for producing interlocking engagement when the upper barrel is rotated, and a bolt for engaging the shank, retaining the yoke in locked position, the upper barrel having a recess into which the bolt is movable for releasing the shank of the yoke.

3. In a lock, a casing, a spring operated yoke mounted in the casing and including a shank, an upper barrel and a lower barrel in alinement therewith, means for moving the upper barrel by the rotation of the lower barrel, spring controlled and key controlled pins mounted in the lower barrel, spring held pivoted means carried by the upper barrel, means formed in the wall of the casing for engaging the pivoted means, the yoke being adapted to release the engaging means, resilient means for rotating the upper barrel, and a bolt for engaging the shank, retaining the yoke in locked position, the upper barrel having a recess into which the bolt is movable for releasing the shank of the yoke.

4. In a lock, a casing having a bore and a cam slot therein, a spring operated yoke mounted in the bore and including a shank, and including means engaging the slot, whereby partial rotation is imparted to the shank and yoke, an upper barrel and a lower barrel in alinement with each other, means for moving the upper barrel by the rotation of the lower barrel, a bolt for engaging the shank, retaining the yoke in locked position, the upper barrel having a recess into which the bolt is movable for releasing the shank of the yoke.

In testimony whereof I affix my signature.

ARNOLD J. FRITH.
